Primary Examiner — Eric Goodman*Assistant Examiner* — Ryan Harvey(74) *Attorney, Agent, or Firm* — Ostrolenk Faber LLP(57) **CLAIM**

I claim the ornamental design for a four wheeled vehicle, as shown and described.

DESCRIPTION

FIG. 1 is a front right perspective view of a four wheeled vehicle;

FIG. 2 is a rear left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the article that form no part of the claimed design.
